Attorney.

UNITED STATES PATENT OFFICE.

CHARLES F. OSGOOD, OF CLAREMONT, NEW HAMPSHIRE, ASSIGNOR TO SULLIVAN MACHINERY COMPANY, A CORPORATION OF MASSACHUSETTS.

HOISTING MECHANISM.

Application filed January 19, 1922, Serial No. 520,387. Renewed August 9, 1928.

My invention relates to hoisting mechanisms, and more particularly to hoisting mechanisms of the portable type.

An object of my invention is to provide an improved hoisting mechanism. Another object of my invention is to provide an improved hoisting mechanism of the portable type which shall be very compact and in which a motor of relatively large power may be employed. A still further object of my invention is to provide an improved hoisting mechanism in which a motor of relatively large power and of the very high speed type may be employed with improved reduction gearing whereby the winding speed of the hoisting mechanism may be kept at the desired rate. Other objects and advantages of my invention will hereinafter more fully appear.

In the accompanying drawings I have shown for purposes of illustration one form which my invention may assume in practice.

In these drawings,—

The view is a central vertical section through the illustrative embodiment of my improved hoisting mechanism.

I have shown the illustrative embodiment of my improved hoisting mechanism as comprising a frame 1 having upstanding supports 2 and 3 at the opposite ends thereof, these supports forming journals respectively for a collar 4 which is formed on an end plate 5 attached to a drum member 6, and for a collar 7 attached to a plate 8 which will be hereafter more fully described. Within the collars 4 and 7 are bearings 9 and 10, respectively, and in these bearings are journaled shafts 11 and 12, which shafts are secured to the opposite end plates 13 and 14 of a cylindrical motor housing 15.

The motor housing is bored to form intercommunicating cylindrical rotor chambers 16 and 17, in which there are rotatably disposed intermeshing rotors 18 and 19 to which fluid is supplied from an inlet port 20 by way of an inlet passage 21 extending through the shaft 12. The rotors 18 and 19 have intermeshing teeth 22 formed thereon; and these cooperate to form expanding pockets to which the motive fluid is admitted. This motive fluid exhausts to end exhaust chambers 23 and 23' between the ends of the rotors and the end plates 13 and

14 and thence in any suitable manner to the atmosphere. It will be noted that the drum 6 is journaled upon the periphery of the motor housing 15.

The shaft 24, to which the rotor 18 is secured, projects through the end plates 13 and 14 and carries thereon driving pinions 25 and 26 which mesh respectively with driving gears 27 and 28 which are journaled upon stub shafts 29 and 30, respectively, secured to the motor housing closure plates 13 and 14. The driving gear 27 meshes with an internal gear 31 which is formed on the inside of a flange 32 secured to the drum 6, the flange 32 having a braking surface 33 upon its exterior with which a brake band 34 and manual brake applying means 35 co-operate. The driving gear 28 meshes with an internal gear 36, serving as a reaction gear, which is formed within a rim 37 formed upon the plate member 8 which serves as a reaction member. A braking surface 38 formed upon the exterior periphery of the rim 37 is engaged by a brake band 39 under control of a manual brake applying means 40, whereby the reaction member 8 may be released or held stationary as desired.

The tooth ratios between the gears 25, 27 and 31 and 26, 28 and 36 may be arranged as desired to effect any desired speed reduction whatever. For example, let it be assumed that the pinion 26 in ten revolutions will cause the pinion 28 to rotate a sufficient number of times to carry the motor casing one complete revolution by reason of the mesh between the gear 28 and the then stationary gear 36. Now if the number of teeth upon the pinions 25, 27 and 31 is properly selected, it will be possible to have almost any desired movement of the drum. For example, assume that the ratio is such that the gear 27 would roll only nine-tenths of the way around the internal gear 31, while the motor casing is making a complete turn; then it will be evident that during a complete turn of the motor casing the internal gear 31 would have to be turned bodily one-tenth of a revolution, and that as a result the drum 6 would be turned one-tenth of a revolution during ten revolutions of the pinion 26, or a reduction in speed of one hundred to one would be obtained. It will be clearly evident that any other desired reduction may be provided by means of my

improved mechanism by simply changing the tooth ratios of the several component gears.

From the foregoing description the mode of operation of this device will already be apparent and it will suffice to state that when the plate 8, which acts as the reaction member for the rotatable motor, is held stationary, and so the reaction gear 36 is held stationary, the motor will rotate inside the drum and will drive the drum at a reduced speed; while, if the brake band 39 is released and the brake band 34 applied, the plate 8 will rotate while the drum may be held stationary. The possibility of allowing the drum to run backward when rope is pulled off will be obvious, and also the possibility of braking the motor by the air supply in such manner as to stop the load at any given desired position will likewise be obvious.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a hoisting mechanism, a hoisting drum, a motor having intermeshing rotors disposed within said drum and having a casing upon which said drum is rotatably journaled, means for connecting said drum and motor in driving relation including a gear carried by said drum, a normally stationary gear, and motor driven gears rotatable on pivots fixed to said casing and meshing with said first and second mentioned gears.

2. In a hoisting mechanism, a rotatable winding drum and driving means therefor including a motor disposed within said drum and having intermeshing rotors whose axes trace, during operation of said motor, surfaces of revolution whose elements are parallel to elements of the surface of said drum, and driving gearing including driving pinions at opposite ends of one of said rotors, driving pinions with which said first mentioned driving pinions mesh and which are rotatable on pivots fixedly carried by said motor, and gears one secured to said drum and the other mounted coaxially with said drum and fixed or released at will with which said second mentioned pinions mesh.

3. In a hoisting mechanism, a rotatable winding drum and driving means therefor including a motor disposed within said drum and having intermeshing rotors whose axes trace, during operation of said motor, surfaces of revolution whose elements are par-

allel to elements of the surface of said drum, and driving gearing including driving pinions at opposite ends of one of said rotors, driving pinions with which said first mentioned driving pinions mesh and which are rotatable on pivots fixedly carried by said motor, and internal gears one secured to said drum and the other mounted coaxially with said drum and fixed or released at will with which said second mentioned pinions mesh.

4. In a hoisting mechanism, a rotatable winding drum, driving means therefor including a motor within said drum having relatively movable elements coacting to produce power and also having a pair of rotatable final power transmitting elements for transmitting the power produced by coaction of said first mentioned elements, and similar gear trains at opposite ends of said motor driven by said final power transmitting elements and each including a plurality of gear elements beyond said power transmitting elements, the final gear of one of said trains being fixed to said drum and the final gear of the other being mounted coaxially with the drum and means for controlling rotation of the second mentioned final gear to hold the same stationary or to permit rotation of the same at will.

5. In a hoisting mechanism, a rotatable rope winding drum, a motor having a casing housed therein, driving connections between said drum and motor including a stationary gear, a gear carried by said drum, said gears disposed wholly outside said casing, and motor driven gears carried by and rotatable relative to said casing and meshing with said stationary and drum carried gears respectively, and means for supporting said driven gears at opposite ends of said casing.

6. In a hoisting mechanism, a drum, a motor disposed therein, said motor comprising a rotatable housing and a plurality of intermeshing rotors therein extending lengthwise of the motor, and means for driving said drum by said motor comprising gear mechanism disposed at each end of said motor, and means whereby said gear mechanism at one of said ends effects rotation of said housing while the gearing at the other end effects drum rotation, said gear mechanisms including pinions carried by and on each end of one of said rotors.

7. A hoisting mechanism comprising a drum, a driving motor therefor having a casing, supporting means for said drum and motor supporting the same to permit relative rotation between said drum and casing, reduction driving gearing between said motor and drum for effecting drive of said drum relative to said casing including an internal gear freely rotatable when said drum is idle, a pinion carried by said motor,

and a gear carried by said motor and meshing with said internal gear and pinion, and means for holding said internal gear stationary to produce rotation of said drum.

5 8. In a hoisting mechanism, a rotatable rope winding drum, a motor housed therein having a rotatable casing, driving connections between said drum and motor including a stationary gear, a gear carried by said 10 drum, and motor driven gears carried by said casing and meshing with said stationary and drum carried gears respectively, said driven gears being disposed at opposite ends of said casing and outside the ends 15 of the latter.

9. A hoisting mechanism comprising a drum, driving means therefor including a motor having a rotatable casing disposed within said drum and a pair of coaxial 20 driving pinions disposed outside said casing with their axes extending longitudinally of the drum, a reaction member, reduction gearing including one of said pinions operatively connecting said reaction member 25 and motor to produce rotation of said casing, and reduction gearing including the other of said pinions operatively connecting said motor and drum in driving relation to further reduce the speed at which the drum 30 is driven.

10. A hoisting mechanism comprising a drum, driving means therefor including a motor disposed therein having a rotatable

frame, bearings on said frame, an orbitally movable element carried by said frame in 35 said bearings with its axis parallel to but offset from the drum axis and a pair of orbitally movable driving pinions attached, to the outside of said bearings, to and driven by said rotatable element on the same axis 40 therewith, a reaction member, reduction gearing including one of said orbitally movable driving pinions operatively connecting said reaction member and motor to produce rotation of said casing, a gear secured to 45 said drum, and reduction gearing including said last mentioned gear and the other of said orbitally movable driving pinions operatively connecting said motor and drum in driving relation to further reduce the 50 speed at which the drum is driven.

11. A hoisting mechanism comprising a drum, a gear secured to said drum coaxially therewith, and driving means operatively connected to said gear to rotate said drum 55 including a reaction gear disposed coaxially therewith and a motor disposed in said drum having a rotatable casing, said casing providing a bearing surface on its periphery for rotatably supporting said drum, and a 60 pair of orbitally movable gears, one meshing with each of said coaxial gears and each moving orbitally during full speed drum drive.

In testimony whereof I affix my signature.
CHARLES F. OSGOOD.
